SUBMERSIBLE HEATER WITH HEATED FUEL VALVE

Joseph Kohorst, Rte. 1, Arcadia, Iowa
Filed Apr. 1, 1963, Ser. No. 269,386
12 Claims. (Cl. 126—360)

This invention relates to improvements in needle valves and more particularly to valves of this type which are used in apparatus intended for use under conditions which expose it to very cold temperatures. Still more particularly, this needle valve is designed for use in tank heaters and submersible burners of the type exemplified in my United States patent, No. 3,021,833.

In the type of heater unit used in the device shown in such patent, fuel oil is burned and since the entire heater is located out-of-doors to keep watering tanks from freezing in a well-known manner, I have found that considerable difficulty is encountered at times in maintaining a properly adjusted flow of fuel. For example, if a needle valve control is finely adjusted for a proper fuel flow or drip at or about freezing temperature, a sudden drop in temperature as frequently occurs overnight will so thicken the fuel oil that the fuel supply to the burner either becomes wholly inadequate or more likely will cease altogether. Likewise a fuel flow control adjusted to extremely cold temperatures will provide too much fuel when temperatures rise materially, and since it is not always convenient or desirable to inspect and adjust the fuel control with each such temperature fluctuation, I have overcome this problem by this invention for which one of the important objects is to provide a new needle valve construction which is heated and thus not only eliminates any effect on the needle valve itself from changes in ambient temperature, but also provides heat to the fuel oil for proper flow irrespective of the surrounding temperature.

Another important object contemplates the provision of a needle valve of the above class which has a portion of its structure in contact with a heated portion of the heater unit so as to receive heat therefrom by conduction.

A further feature of the present invention resides in a needle valve construction as characterized wherein the needle valve control assembly is interposed in a fuel line at a point remote from the discharge end of such line.

Further objects and the more obvious advantages of the invention will be mentioned or else appear plainly from the description which follows.

To attain these objects and such further objects as may appear herein, or be hereinafter pointed out, reference is made to the accompanying drawings forming a part hereof, in which:

FIG. 1 is a perspective view of a heater unit with my new needle valve associated therewith, the heater being illustrated only generally to show the environment in which this invention is used.

FIG. 2 is an enlarged elevational view of this invention, and

FIG. 3 is an enlarged longitudinal section view taken on the line 3—3 of FIG. 2.

Referring to the drawings, the heater designated generally by the numeral 10 is shown to illustrate the type or character of heating device with which my new needle valve assembly 12 is used, and for purposes of this application, no invention is claimed in such heater since the same is now the subject of my United States patent, No. 3,021,833. I shall, however, refer to and identify certain structural portions of heater 10 which are common to devices of this type and with which valve 12 cooperates as will later appear.

2

While heater 10 may be used as a room heater, if desired, it was especially designed for use as a tank heater to keep water from freezing in out-of-doors animal watering troughs and it is in connection with this use and purpose that valve 12 has particular utility, although it will be appreciated as this description proceeds that it is not limited thereto from the standpoint of an efficient fuel flow control device.

Heater 10 includes generally a housing 14 which, when used as a tank heater, will be submerged in water to be heated and includes the upstanding stacks 16 and 18 which are used for draft control in a manner not important to this disclosure. A clamp 20 on stack 18 provides means for attaching heater 10 to a watering trough or tank (not shown). A third stack 22 on housing 14 provides a means of access to the interior of the housing and for communication with a combustion chamber or burner unit located therein and indicated generally by the numeral 23, such burner unit being adapted to supply heat to housing 14. In this regard while any suitable heater may be employed for heating housing 14, I have found the device described in my U.S. Patent No. 3,021,833 to be very satisfactory. The source of heat for unit 10 is the burning of fuel oil for which a supply tank is shown at 24 adjustably carried by brackets 26 which are attached to stack 16. It will thus be appreciated from the description so far that the fuel reservoir 24 and fuel line for delivering fuel through stack 22 to the burner assembly are exposed to the atmosphere and thus subject to whatever temperature conditions are present and it is also pointed out that when housing 14 is submerged as indicated above, the exact level of the water relative to heater 10 is not material so long as it is not high enough to overflow stack 22. Since the heater unit 10 by its very purpose described is used only when freezing temperatures are prevalent, the difficulties of proper fuel flow control as outlined are present.

In overcoming this problem, I have devised my new needle valve assembly 12 which I will now describe. Assembly 12 includes an elongated vertically disposed fuel flow line or conduit 28 of pipe or tubing material having a branch line 30 intermediate the ends thereof, said line 30 being provided with a suitable fitting 32 for flow connection to the fuel supply tank or reservoir 24 in a well-known manner. The lower end of line 28 is removably connected to one end of a collar-like coupling or fitting 34 and to the other end of fitting 34 there is similarly secured a conduit extension 36 of like size and material which is formed in a circuitous path, as will be referred to in more detail, and which terminates in a downwardly directed cap 38 that is provided with a funnel-shaped or tapered opening 40.

Conduit extension 36, at a point below fitting 34, defines a U-shape curve 42, being either bent or otherwise so formed as to provide a vertical length 44 of conduit 36 which extends upwardly to point 46 in spaced parallel relationship to conduit portion 28. At point 46, conduit 36 is further bent or turned to extend horizontally as at 48 away from conduit portions 36 and 44 to point 50 where it is further bent or turned to extend downwardly in spaced parallel relationship to conduit portions 36 and 44 and terminates in its discharge end defined by cap 38, the plane of opening 40 on cap 38 being higher than the plane of point 42.

Within the coupling or fitting 34 there is mounted a needle valve valve seat 54 (FIG. 3) of well-known construction which includes the restricted fuel passageway 56 communicating with conduit extension 36. A cap 58 is removably attached to the upper end of conduit 28 and is provided with the vent hole 60 for the escape of air if necessary so as not to impede the flow of oil from tank 24. An elongated needle valve 62 is journaled with con-

duit 28, having its needle point 64 extending to valve seat 54 for cooperation therewith in the usual manner, and being threadably journaled at its upper end portion 66 in cap 58. Such end portion 66 carries an operating knob 68 on the upper end, and a lock washer or nut 70 is also mounted on portion 66 for locking valve 62 in any desired position of adjustment relative to seat 54.

In the use and operation of valve assembly 12 as described, the same is mounted on heater unit 10 as shown in FIG. 1. In this respect, fitting 32 on branch conduit 30 is attached to reservoir 24 for a gravity flow feed of fuel in valve assembly 12. The operating knob 68 will extend upwardly for convenient access and manual manipulation and the point 42 of assembly 12 will rest upon the upper surface of housing 14 closely adjacent but exteriorly of stack 22. Length 44 of conduit extension 36 will also be disposed exteriorly of stack 22 and length 52 of such conduit extension will extend axially into stack 22 so that opening 40 is properly located for delivering fuel oil to the burner unit located therein.

Preferably I secure an open top shield or guard enclosure 72 to housing 14 adjacent stack 22 in which valve assembly 12 is placed as shown and in the bottom of such enclosure there are parallel spaced stop bars 74 extending parallel to the longitudinal axis of housing 14 which provide a restricted track in which U portion 42 of assembly 12 is seated. The purpose of such bars 74 is to embrace the U portion 42 and thereby prevent such portion from becoming accidentally slid or moved transversely of the longitudinal axis of housing 14 so as to affect the desired axial alignment of opening 40 within stack 22. In this regard, the slidability of reservoir 24 on brackets 26 affords means for adjusting the alignment of length 52 of conduit 36 within stack 22 in a direction parallel to the longitudinal axis of housing 14. A drain opening 76 is provided in one side of enclosure 72 near the bottom thereof to facilitate the draining of water therefrom whenever the unit 10 may be removed from a watering tank for storage or repairs.

It is pointed out that the plane of length 48 of conduit 36 is below the plane of the branch line 30 and will thus be below the bottom of reservoir 24 so that gravity feed through opening 40 is not affected by the upward travel of fuel through conduit length 44.

It will be appreciated that with assembly 12 in direct contact with housing 14 at point 42, the assembly 12, particularly in the area of coupling 34 will be well heated so that the metal in the needle valve and valve seat will not be materially affected by changes in outside temperatures. Likewise the fuel oil within assembly 12 is warmed or heated sufficiently to assure proper flow and by using material for assembly 12 that is highly conductive of heat, it is apparent that some heat is of course transmitted to reservoir 24. By the use of enclosure 72, the lower portion of conduit 28, length 44 and the needle valve structure in fitting 34 are all jacketed in a body of heated water which increases the portion of assembly 12 exposed to a source of heat and thereby increases the efficiency of operation of the fuel flow control.

From the foregoing description it is thought that a full understanding of the construction and operation of this invention will be had and the advantages of the same will be appreciated.

It will be understood that the phraseology employed herein is for the purpose of description and not for limitation and that modifications and changes in the construction and arrangement of this invention can be made within the scope of what is claimed, without departing from the spirit and purpose thereof. It is thus intended to cover by the claims, any modified forms of structure or mechanical equivalents which may be reasonably included within their scope.

I claim:

1. In a heater unit of the type designed for use out-of-doors in cold temperatures to keep water from freez-

ing in a tank or trough, said heater having a submersible housing, a fuel oil burner means for heating said housing and a fuel oil reservoir exposed to the atmosphere, the combination therewith of an improved needle valve assembly comprising:

a fuel oil flow line connected for flow communication to said reservoir and having a discharge end disposed in operable relationship relative to said burner means,

a needle valve seat in said flow line,

a needle valve in said flow line operable with said valve seat and with manual means for adjusting the same,

said flow line being provided with a vent opening, and means positioning a portion of said flow line in direct contact with a portion of said housing to receive heat therefrom by conduction for heating said valve seat.

2. In a heater unit of the type designed for use out-of-doors in cold temperatures to keep water from freezing in a tank or trough, said heater having a submersible housing, a fuel oil burner means for heating said housing and a fuel oil reservoir exposed to the atmosphere, the combination therewith of an improved needle valve assembly comprising:

a fuel oil flow line connected for flow communication to said reservoir and having a discharge end disposed in operable relationship relative to said burner means,

a needle valve seat in said flow line intermediate the ends thereof,

a needle valve in said flow line operable with said valve seat and with manual means for adjusting the same,

said flow line being provided with a vent opening, and a portion of said flow line adjacent the location of said needle valve seat being in direct contact with a portion of said housing to receive heat therefrom by conduction for heating said valve seat.

3. In a heater unit of the type designed for use out-of-doors in cold temperatures to keep water from freezing in a tank or trough, said heater having a submersible housing, an enclosed fuel oil burner means for heating said housing and a fuel oil reservoir exposed to the atmosphere, the combination therewith of an improved needle valve assembly comprising:

a fuel oil flow line connected for flow communication to said reservoir and having a discharge end disposed within said enclosed burner means for operable relationship relative thereto,

a needle valve seat in said flow line,

a needle valve in said flow line operable with said valve seat and with manual means for adjusting the same,

said flow line being provided with a vent opening, and means positioning a portion of said flow line exteriorly of said enclosed burner means in direct contact with a portion of said housing to receive heat therefrom by conduction for heating said valve seat.

4. In a heater unit of the type designed for use out-of-doors in cold temperatures to keep water from freezing in a tank or trough, said heater having a submersible housing, a fuel oil burner means for heating said housing and a fuel oil reservoir exposed to the atmosphere, the combination therewith of an improved needle valve assembly comprising:

a fuel oil flow line connected for flow communication to said reservoir and having a discharge end disposed in operable relationship relative to said burner means,

a needle valve seat in said flow line,

a needle valve in said flow line operable with said valve seat and with manual means for adjusting the same,

said flow line being provided with a vent opening, and

means positioning a portion of said flow line in direct contact with a portion of the exterior of said housing to receive heat therefrom by conduction for heating said valve seat.

5. In a heater unit of the type designed for use out-of-doors in cold temperatures to keep water from freezing in a tank or trough, said heater having a submersible housing, an enclosed fuel oil burner means for heating said housing and a fuel oil reservoir exposed to the atmosphere, the combination therewith of an improved needle valve assembly comprising:

a fuel oil flow line connected for flow communication to said reservoir and having a discharge end disposed within said enclosed burner means for operable relationship relative thereto,

15 a needle valve seat in said flow line,

a needle valve in said flow line operable with said valve seat and with manual means for adjusting the same,

said flow line being provided with a vent opening, and 20 means positioning a portion of said flow line exteriorly of said enclosed burner means in direct contact with a portion of the exterior of said housing to receive heat therefrom by conduction for heating said valve seat.

6. In a heater unit of the type designed for use out-of-doors in cold temperatures to keep water from freezing in a tank or trough, said heater having a submersible housing, a fuel oil burner means for heating said housing and a fuel oil reservoir exposed to the atmosphere, 30 the combination therewith of an improved needle valve assembly comprising:

a fuel flow line connected intermediate its ends for flow communication to said reservoir,

said flow line having a restricted discharge opening on 35 one end disposed in operable relationship relative to said burner means,

the other end of said flow line being provided with a vent opening,

a needle valve seat in said flow line intermediate said 40 discharge opening and said point of connection to said reservoir,

a needle valve in said flow line operable with said valve seat,

said needle valve including an elongated shank projecting from said other end of said flow line,

manually operable control means on said projecting end of said needle valve, and

means positioning a portion of said flow line in direct 50 contact with a portion of said housing to receive heat therefrom by conduction for heating said valve seat.

7. A device as defined in claim 6 wherein:

an enclosure surrounds said burner means,

said discharge opening in said flow line is within said 55 enclosure, and

the point of contact of said flow line with said housing is exteriorly of said enclosure.

8. A device as defined in claim 6 wherein the point of contact of said flow line with said housing is adjacent the location of said valve seat.

9. A device as defined in claim 6 wherein said flow line contacts the exterior of said housing.

10. A device as defined in claim 6 including means on said housing engageable with said flow line to hold it against movement relative thereto.

11. In a heater unit of the type designed for use out-of-doors in cold temperatures to keep water from freezing in a tank or trough, said heater having a submersible housing, a fuel oil burner means for heating said housing and a fuel oil reservoir exposed to the atmosphere, the combination therewith of an improved needle valve assembly comprising:

a fuel oil flow line connected for flow communication to said reservoir and having a discharge end disposed in operable relationship relative to said burner means,

15 a needle valve seat in said flow line,

a needle valve in said flow line operable with said valve seat and with manual means for adjusting the same, said flow line being provided with a vent opening, means positioning a portion of said flow line in direct contact with a portion of said housing to receive heat therefrom by conduction for heating said valve seat, and

20 means on said housing engageable with said flow line to hold it against movement relative thereto.

12. In a needle valve assembly for a fuel oil burner of the type used out-of-doors in cold temperatures:

an elongated fuel flow line defining an irregular path, means for attaching said flow line to a source of fuel supply,

said flow line being provided with a vent opening remote from its point of attachment to a source of fuel supply,

said flow line having a discharge end adapted for disposition in operable relationship to a burner unit, a needle valve seat in said flow line spaced from said discharge end,

a needle valve in said flow line operable with said valve seat,

means for adjusting said needle valve relative to said valve seat, and

said flow line being provided with means to receive heat supplied by the burner unit with which said discharge end is associated for heating said valve seat.
